UNITED STATES PATENT OFFICE

158,379

ASH TRAY

Harry S. Hawkins, Ann Arbor, Mich.

Application October 25, 1948, Serial No. 149,277

Term of patent 7 years

(Cl. D85—2)

To all whom it may concern:

Be it known that I, Harry S. Hawkins, a citizen of the United States of America, residing at Ann Arbor, in the county of Washtenaw and State of Michigan, have invented a new, original, and ornamental Design for an Ash Tray, of which the following is a specification, reference being had to the accompanying drawing, forming a part thereof, wherein:

Fig. 1 is a perspective view of an ash tray showing my new design;

Fig. 2 is a side elevational view thereof; and
Fig. 3 is a top plan view thereof.

I claim:

The ornamental design for an ash tray, substantially as shown.

HARRY S. HAWKINS.
